US00D928080S

(12) **United States Design Patent** (10) **Patent No.:** **US D928,080 S**
(45) **Date of Patent:** ** *Aug. 17, 2021

(54) **BATTERY**

(71) Applicant: **LiBEST INC.**, Daejeon (KR)

(72) Inventors: **Joo Seong Kim**, Daejeon (KR); **Seung Gyu Lim**, Gwangju (KR); **Jin Hong Ha**, Daejeon (KR); **Gil Ju Lee**, Daejeon (KR)

(73) Assignee: **LiBEST INC.**, Daejeon (KP)

(*) Notice: This patent is subject to a terminal disclaimer.

(**) Term: **15 Years**

(21) Appl. No.: **29/695,926**

(22) Filed: **Jun. 24, 2019**

(51) LOC (13) Cl. **13-02**

(52) U.S. Cl.

USPC **D13/103**

(57) **CLAIM**

The ornamental design for a battery, as shown and described.

DESCRIPTION

FIG. 1 is a perspective view of a battery showing our new design;

FIG. 2 is a top plan view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken line representations in the figures show unclaimed environment, and thus form no part of the claimed design.

1 Claim, 7 Drawing Sheets
